UNITED STATES PATENT OFFICE.

HENRY F. HYMAN AND G H. HAY, OF HOUSTON, TEXAS.

SWITCH-OPERATING MECHANISM.

No. 892,838.

Specification of Letters Patent.

Patented July 7, 1908.

Application filed August 19, 1907. Serial No. 389,316.

To all whom it may concern:

Be it known that we, HENRY F. HYMAN and G H. HAY, citizens of the United States, and residents of Houston, in the State of 5 Texas, have invented certain new and useful Improvements in Switch-Operating Mechanism, of which the following is a specification.

The object of the invention is to provide means operated by an approaching car for 10 closing a switch which may have been left open, thus insuring a clear main line.

In the preferred construction which we have devised as an embodiment of the invention the switch is thrown open or closed by 15 an ordinary switch stand, but there is a releasable latch interposed between the stand and the switch and this latch is retracted from a distance by the approaching car or locomotive, permitting the switch to close, if 20 it has been left open, under the influence of a spring. The switch may be restored to operative connection with its stand or operating lever by simply moving the lever to position corresponding to a closed switch, permitting the latch to reconnect the switch 25 with the stand.

In the accompanying drawing, Figure 1 is a plan of a track section including a switch and other necessary parts of the mechanism. 30 Fig. 2 is a transverse section through so much of the switch and associated mechanism as is necessary to illustrate the invention, and, Fig. 3 is a fragmentary central longitudinal section of a portion of track showing 35 the distant latch operating mechanism.

Reference numeral 1 indicates the switch points connected in the usual manner by a rod 2. A spring 3 acting between a collar or rod 2 and a stationary abutment urges the 40 switch to closed position. At one end rod 2 is provided with a socket 4 in which fits the end of another rod 5 which may be termed for convenience, a link. Rod 2 has a hole 6 passing through the socket, and link 5 is provided with a hole 7 adapted ordinarily to 45 register with hole 6. Link 5 is connected in any approved manner with lever 8 of a switch stand by which the switch is operated.

50 Ordinarily holes 6 and 7 in socket 4 and link 5 are in register, and latch 9 passes through both, connecting rod 2 and link 5 together so that they form an operative unit. The latch is pivotally connected to rod 2 and 55 tends to enter the holes by influence of gravity. A spring 10 acting on a link 11 which

engages the latch may also be provided, to insure the proper action of the latter.

The latch is disengaged from hole 7 by means of a bell-crank 12 pivotally mounted 60 in a fixed support 13. One arm of the bell-crank is suitably shaped to engage the underside of the latch, and the other arm is connected with a chain 14 which passes around a pulley 15 mounted on a fixed support and 65 along the track for a suitable distance in the direction in which the switch faces. At this point another bell-crank 16 is pivotally mounted between the rails. The bell-crank comprises a shaft 17, a cam-shaped arm 18, 70 to be acted on by the car or locomotive, and another arm 19 connected with the end of the chain. The car or locomotive is provided with a roller 20, or other suitable device, to act on the cam shaped arm 18 of 75 bell crank 16.

As the locomotive approaches the switch, if the switch be open, roller 20, or equivalent device carried by the locomotive, strikes arm 18 or bell crank 16, and through arm 19 80 pulls chain 14, which actuates bell-crank 12 and withdraws latch 9 from hole 7 in link 5, permitting the switch to close under the influence of its spring in the manner above described, and giving the train a clear main 85 line.

If desired, the switch rod 2 may be connected by suitable mechanism 21 to a semaphore or other signal, so arranged as to give the engineer an indication of the condition 90 of the switch.

We claim:

An automatic switch closing device comprising a tie-bar connecting the points and having a socket, a link entering the socket, a 95 switch lever connected to the link, registering holes in the link and socket, a latch pivoted to the tie-bar and having a hook adapted to enter the holes, a bell-crank carried by the tie-bar and having one arm 100 engaging the latch, a chain connected to the other arm of the bell-crank, a device distant from the switch arranged to be acted on by a car and connected to the chain, and means normally tending to close 105 the switch.

H. F. HYMAN.
G H. HAY.
